WINDING MECHANISM FOR MAGNETIC RECORDERS

Fernand de Clerck, Marcinelle, Belgium, assignor
to Ateliers de Constructions Electriques de
Charleroi, Brussels, Belgium, a Belgian firm

Application October 13, 1952, Serial No. 314,501

Claims priority, application France
October 26, 1951

3 Claims. (Cl. 242—75)

1

The present invention relates to an improved mechanism for winding and unwinding magnetizable tape on magnetic recorders wherein the said magnetizable tape is of great width and/or great length. More particularly, the invention has especial relation to the winding unit of such mechanism.

Copending application, Ser. No. 215,215, filed March 13, 1951, now abandoned, describes a mechanism of this character, the purpose of which is to assure correct operation and perfect magnetic reproduction at any point whatsoever of the tape. More particularly, the mechanism of the said copending application is designed toward the achievement of correct winding of the magnetizable tape onto a winding cylinder or drum—such winding involving a translational movement of the tape along a path fixed in space—without transverse sliding movement toward either of its edges, and also toward the achievement of a uniform winding without abnormal increase due to enlargement of the diameter of the assembly formed by the winding cylinder and the part of the magnetizable tape already wound thereon.

In the arrangement according to the said copending application—which arrangement, reduced to lowest terms, comprises an unwinding cylinder for the tape, an exploring table over which the tape coming from the unwinding cylinder passes, magnetic heads which explore the tape as it passes over said table, a feed roller device which actuates the tape, i. e. imparts translational movement thereto, and a winding cylinder or drum on which the explored tape is wound—the lateral guiding of the tape is assured by the following means:

(a) The speed of advance of the magnetizable tape is solely conditioned by the rotation of a driving roller;

(b) The mechanical tension of the magnetizable tape is equalized by springs cooperating with levers which support control rollers, the rotation of the winding and unwinding cylinders being controlled intermittently so as to maintain this mechanical tension within admissible limits, namely: below a certain maximum value for the unwinding and above a certain minimum value for the winding.

This construction gives rise to a certain "slack" in the magnetizable tape which helps to prevent lateral sliding of the latter.

Moreover, buckling of the paper on the winding cylinder is prevented, according to the device of the copending application by the following means:

2

(a) The winding drum is equipped with a yieldable pressure heel in such manner as to press the successive wound layers of magnetizable tape against one another;

(b) A sheet of metal or of metallized material is interposed between the last two layers of magnetizable tape and slides between them and such sheet, being retained by spring means.

While the construction according to the said application is well suited for its intended purpose, the regulation of the limits between which the mechanical tension of the magnetizable tape varies, in the aforescribed prior mechanism, is quite delicate, so that an accidental slight mal-adjustment or poorly determined limits can occasion a lateral sliding. The metallized sheet designed to prevent buckling is also sensitive and may on occasion constitute a source of difficulty in the proper operation of the mechanism.

A primary object of the present invention is the embodiment of improved winding mechanism, designed primarily for use in winding and unwinding mechanism of the type of the said copending application, and which is free of the aforesaid inconveniences.

Briefly stated, the new winding mechanism—the unwinding and feeding mechanisms for the magnetizable tape advantageously remaining the same as in the copending application—has the following characteristics:

1. The winding mechanism is constituted by a winding drum or cylinder provided with an individual driving motor, and by auxiliary means designed to impart intermittent rotary movement to said cylinder, the starting of the said driving motor being effected progressively;

2. The winding cylinder is actuated by an intermittent rotary movement, the angular velocity of which increases gradually from the state of rest, the said velocity reaching a value such that the linear winding velocity of the magnetizable tape on the said cylinder is greater than the rate of travel of the said tape;

3. The auxiliary device comprises a resistance with a negative temperature coefficient, inserted in series in the feed circuit of the driving motor of the winding cylinder, so that the angular velocity of the said driving motor increases progressively starting from the state of rest;

4. The auxiliary device comprises a switch inserted in series in the feed circuit of the driving motor of the winding cylinder, the said switch being kept closed by a spring, a feeler system in contact with the magnetizable tape also acting on the switch, in such manner that the latter is kept open by the action of the

feeler system when the mechanical tension of the said magnetizable tape exceeds a certain maximum value;

5. The feeler system is made in such a way that contact with the magnetizable tape takes place only in the median portion of the said magnetizable tape, relatively to its width.

A presently-preferred relationship of parts according to the invention is shown diagrammatically and by way of example only, on the accompanying sheet of drawings, wherein:

Fig. 1 is a diagrammatic showing of the relationship of parts of the present invention at one stage in the winding operation;

Fig. 2 is a similar showing at a different stage in the winding operation; and

Fig. 3 is a graphic representation of the variation in rotational speed of the motor driving the winding drum or cylinder, as a function of the time.

The magnetizable tape 1, after being delivered from the unwinding cylinder (not shown) and after being passed over the exploring table 3, where it is explored by the magnetic heads 4, and between the feed rollers 8 and 9, is directly wound on the winding drum 5.

According to the characteristics of the invention, as hereinbefore defined, the winding mechanism has the following particularities:

The winding drum 5 is fixedly mounted on shaft 50 driven by a driving motor 140 (by conventional means, not shown, e. g. a driving belt of the like), in such a way that the maximum linear winding velocity of the magnetizable tape 1 on the drum 5 is higher than the speed of travel of the said tape, this travel (or advance movement) being effected by the roller 8 keyed onto shaft 80 driven by a driving motor (not shown), with the aid of superposed roller 9.

The driving motor 140 is fed from a suitable and conventional source of current 141. In series in the supply circuit, there are intercalated a resistance 142, with negative temperature coefficient, and a switch 143. The switch 143 is kept normally closed by a pull spring 144 integrally connected with the framework of the apparatus, and is controlled by a feeler system, shown diagrammatically at 145, in contact with the magnetizable tape 1.

The feeler system itself may be of any suitable and per se conventional construction. For example, it may be a slidably supported rod having a loop at one end through which the tape passes, thus assuring contact between the tape and the "feeler" end of the rod. The latter is of a length slightly greater than the distance between switch 143 and the tape, when the tape is in "taut" state (Fig. 2).

The operation of the winding mechanism is as follows:

The magnetizable tape 1 being in the position shown in Fig. 1, that is to say, in the "slack" state, the feeler device 145 does not act on the switch 143 and permits the closing of this latter by the action of the spring 144. At this moment the supply circuit of the driving motor 140 is closed.

The resistance 142, with negative temperature coefficient, is conditioned so that, cold, its value is sufficiently high and so that, as a consequence of the difference of potential at its terminals the voltage at the terminals of the motor 140 is insufficient to start the said motor; the magnetizable band 1 therefore continues to become slack.

The heating by Joule's effect of the resistance 142 progressively diminishes its magnitude so

that the driving motor 140, after having started under a low voltage, is subjected to a gradual, but continuous, increase in feed voltage. The magnetizable tape 1 is thus wound onto the winding drum 5, keyed onto the shaft 50 driven by the motor 140, and the linear winding velocity of the magnetizable tape 1 reaches and exceeds the linear rate of travel (advance) imposed by the drum 8, driven by the shaft 80.

10 When the mechanical tension of the magnetizable tape 1 exceeds a maximum admissible value, the action of the feeler device 145 on the switch 143 overbalances that of the spring 144, and the switch 143 opens, thus interrupting the feeding of the driving motor 140. The state shown in Fig. 2 of the drawings is then reached.

Another operating cycle begins when the magnetizable tape 1 no longer has sufficient mechanical tension to balance the action of the spring 144.

20 The graph shown in Fig. 3 shows the course of the variation of the rate of rotation of the driving motor 140 in time. It can be seen on this graph that, although the switch 143 is closed at time t_1 , the driving motor 140 starts only at time t_2 , because of the retarding action of the resistance 142. Between the times t_2 and t_3 the rate of rotation gradually increases, and at time t_3 the mechanical tension of the magnetizable tape 1 is sufficient for the feeler device 145 to open the switch 143. The driving motor is then stopped at time t_4 .

After a certain time of stoppage a new operating cycle is repeated in $t_4 \dots t_4'$.

35 It can readily be appreciated that by the temperizing effect of the negative resistance 142 inserted in the supply circuit of the motor 140 a great flexibility and smoothness of operation are obtained.

Having thus disclosed the invention, what I

40 claimed is:

1. A winding mechanism for winding a magnetic recorder tape or the like onto an intermittently rotatable winding cylinder, comprising means for feeding the tape along a path to said winding cylinder, and means for imparting intermittent rotation to said winding cylinder, said last-named means comprising a driving motor for said cylinder and means for controlling the angular velocity of said motor whereby such velocity and the velocity of the driven winding cylinder progressively increase to their maximum, starting from the state of rest, the means for controlling the said angular velocity comprising a resistance with a negative temperature coefficient inserted in series in the feed circuit of said motor whereby, initially, the resistance has a maximum value and, as the resistance heats up, the resistance gradually and progressively decreases.

60 2. A winding mechanism for winding a magnetic recorder tape or the like onto an intermittently rotatable winding cylinder, comprising means for continuously feeding the tape along a path to said winding cylinder whereby, when said winding cylinder is not rotating, tape in slack state accumulates in the path between said cylinder and feeding means, and means for periodically tensioning said tape in its travel from said feeding means to said winding cylinder, said tensioning means comprising an intermittently operated driving motor for said cylinder, the maximum angular speed of rotation of which exceeds the linear speed of travel of said tape along said path, a normally closed switch inserted in series in the feed circuit of said motor,

feeler means in contact with said tape at a point in its travel from said feeding means to said winding cylinder, said feeler means opening said switch when said tape has been tensioned by said tensioning means, and means for controlling the angular speed of rotation of said motor whereby said speed progressively increases to its maximum, starting from the state of rest, the means for controlling the said angular velocity comprising a resistance with a negative temperature coefficient inserted in series in the feed circuit of said motor whereby, initially, the resistance has a maximum value and, as the resistance heats up, the resistance gradually and progressively decreases.

3. A winding mechanism for winding a magnetic recorder tape or the like onto an intermittently rotatable winding cylinder, comprising means for continuously feeding the tape along a path to said winding cylinder whereby, when said winding cylinder is not rotating, tape in slack state accumulates in the path between said cylinder and feeding means, and means for periodically tensioning said tape in its travel from said feeding means to said winding cylinder, said tensioning means comprising an intermittently operated driving motor for said cylinder, the maximum angular speed of rotation of which

exceeds the linear speed of travel of said tape along said path, a normally closed switch inserted in series in the feed circuit of said motor, feeler means in contact with said tape at a point in its travel from said feeding means to said winding cylinder, said feeler means opening said switch when said tape has been tensioned by said tensioning means, whereby rotation of said motor and winding cylinder stops and said slack again accumulates, means for returning said switch to closed position when said slack has accumulated and means for controlling the angular speed of rotation of said motor whereby said speed progressively increases to its maximum, starting from the state of rest, the means for controlling the said angular velocity comprising a resistance with a negative temperature coefficient inserted in series in the feed circuit of said motor whereby, initially, the resistance has a maximum value and, as the resistance heats up, the resistance gradually and progressively decreases.
